FIG. 1

FIG. 2

FIG. 4

FIG. 5

FIG. 3

FIG. 6

FIG. 1 is a front perspective view of a suspension hook for a curtain, or the like, showing my new design, the broken lines indicating the pattern to be continuous;

FIG. 2 is a rear perspective view of the same;

FIG. 3 is a side elevational view of the same;

FIG. 4 is a top plan view of the same;

FIG. 5 is a perspective view of the same, as viewed from the bottom; and

FIG. 6 is a fragmentary enlarged front elevational view of the same.

I claim:

The ornamental design for a suspension hook for a curtain, or the like, substantially as shown and described.
